GUSTAF LUNDSTROM, OF ST. PAUL, MINNESOTA

COMBINATION CHAIR AND STEPLADDER

Application filed May 11, 1931. Serial No. 536,356.

My invention relates to a combination chair and stepladder which may more aptly be designated simply as a chair-ladder, the principal object being to provide an article embodying a foldable stepladder mounted in a new and unique manner in a chair, the construction being such that the stepladder is completely out of view when not in use and within the seat box of the chair. The chair 10 actually comprises the support means and suitable braces for the ladder when the latter is used as such. As a chair there is no new feature, the appearance of same and construction being much the same as an ordinary 15 kitchen or household chair and the stepladder parts are completely inclosed.

In the accompanying drawing,—

Fig. 1 is a top view of the chair.

Fig. 2 is a vertical sectional elevation as on line 2—2 in Fig. 1, with the stepladder in operative position.

Fig. 3 is a full top view of Fig. 2.

Fig. 4 is a sectional view on a horizontal line as 4—4 of Fig. 2, through the seat box 25 of the chair, stepladder parts being omitted.

Fig. 5 is a front elevation of the chair with the stepladder means folded up.

Referring to the drawing by reference numerals, 6 designates the rear posts or up- 30 rights of a chair, 7 the corresponding pair of shorter front posts, both sets of posts connected rigidly by side boards 8 and a rear board 9 connecting the rear posts only. 10 designates a seat board or frame covered with 35 a suitable cover 11 and said seat hinged at 12 to a horizontal cross piece 13 between legs 6.

14 is a cross piece connecting the front legs at a level about even with the bottom edges of the sides 8. 8L are a pair of narrow ledges on 40 a common plane with the parts 14 and extending rearwardly therefrom and fixed to the lower parts of the sides 8. The seat may be raised to upright and rearwardly inclined position against the upper parts of the rear 45 legs, as best shown in Figs. 2 and 3. 15 and 16 are respectively an upper and lower cross piece connecting the rear legs above the seat level and comprising a back rest when the device is used as a chair.

50 17R and 17L are respectively a right and

left rail of a stepladder, both rails counter- parts and each comprising two sections of about the same length and hinged together as at 18. The lower ends of said rails are hingedly mounted as at 19 (Fig. 2) each to a 55 ledge 8L.

20 are the ladder rungs, provided two to each ladder section, the top rung designated 20T and having hingedly secured to its under side, as at 21A an extension board 21 comprising when extended from under rung 20T an extension suitable to place a paint-pot, pail or the like thereon. The abutting edges or ends of the ladder sections are preferably cut on an angular line, and just below said joint, 60 on the lower section, is pivotally secured at 23 a brace 22, the free end of which is adapted to be swung forward to engage frictionally 65 against the seat 10, as best shown in Fig. 2, thus bracing and holding the ladder rigidly 70 in an inclined plane. The ladder is of such length that its upper rung 20T is on a level little above the top of the chair back while the board 21 rests on said back, the said board 75 being provided on its under side with spaced pairs of cleats 24 located so as to engage the top cross piece 15 of the chair.

When it is desired to use the device as a chair the ladder is first collapsed to lie within the seat box, as follows: First, the board 21 is raised, thereby raising the upper ladder section and disengaging the board from the seat back, the said upper ladder section then being swung rearward and down to lie against the front part of the lower ladder section (see arrow 25, Fig. 2). Second, then the folded ladder is released by swinging braces 22 free and allowed to drop down between the sides 8 to rest on the ledges 8L as indicated by 80 dotted lines in Fig. 2. Third, then the seat board 10 is swung forward and down to rest on the tops of members 8 and legs 7 simultaneously. Setting up the ladder is a mere 85 reversal of the procedure just described.

It is obvious that this device may be made to embody a number of modifications of details without departing from the scope and spirit of the invention. For example, a device other than the braces 22 may be used to 90 hold the ladder sections in firm alinement. 95 100

It is further obvious that the rear chair legs 6 comprise the ladder support and they must be so spaced from the front legs as to permit the folded ladder to swing freely down to the lowered position shown dotted in Fig. 2 with the side rails of the lower ladder section resting on the ledges or flanges 8L.

I claim:

1. In a chair having an upright back, a seat frame extending forwardly therefrom and a seat hinged to said frame to swing upwardly and rearwardly against the chair back; said seat frame comprising a quadrangular enclosure normally closed by said hinged seat; a step-ladder comprising sections hinged together in end to end relation to fold one upon the other, one end of one section of the ladder hingedly secured in the lower front part of the seat frame, said ladder adapted to be raised on the latter hinges and its sections alined in an inclined plane toward the back of the chair, and means at the free upper end of the ladder to removably engage the upper end of the chair back.
2. The structure specified in claim 1, and ladder brace means intermediate its ends comprising for each side rail of the ladder a pivoted brace adapted to be swung rearwardly on its hinge and its free end to contact with the seat member near the bottom of the chair.

In testimony whereof I affix my signature.
GUSTAF LUNDSTROM.
